UNITED STATES PATENT OFFICE

VALENTY WROCLAWSKI, OF CHICAGO, ILLINOIS, ASSIGNOR OF ONE-FOURTH TO JOSEPH B. CISZEWSKI, OF CHICAGO, ILLINOIS

CAR-COUPLING DEVICE

Application filed April 3, 1929. Serial No. 352,230.

This invention relates to an improved car coupling device for vehicles such as railway cars, street cars, truck trailers, and the like.

The main objects of my invention are to provide an improved form and arrangement of draw-bar coupling members for avoiding the necessity of manually holding a coupling pin in an inoperative position while cars are being uncoupled and manually placing the pin in operative position after cars are coupled; to provide means for locking a coupling member in an operative position on a draw-bar of a car when two cars are bumped together during coupling thereof without requiring manual operations; to provide improved means for releasably securing a coupling member in an operative position on the draw-bar of a car, which may be conveniently set in an inoperative position and later moved to an operative position by the jarring of coupling operations; to provide an improved coupling pin which automatically retains itself in inoperative position by a wedging action after it has been lifted from an operative position and released, and which may be subsequently jarred into an operative position by the impact of coupling operations.

In the drawings I have shown the specific embodiment of my invention in which:

Figure 1 is a fragmentary plan of my improved coupling.

Fig. 2 is a fragmentary plan showing one of the coupling hooks in open position.

Fig. 3 is a fragmentary section taken on the line 3—3 of Fig. 1.

Fig. 4 is a fragmentary section similar to Fig. 3 showing the pin in an inoperative position.

Fig. 5 is a fragmentary section showing the pin in a raised position.

Fig. 6 is a fragmentary detail of the coupling pin showing the parts thereof in spaced relation.

Fig. 7 is a side elevation of the improved coupling pin.

In general, my improved car coupling device comprises a coupling member or hook pivotally mounted on a draw-bar head. The draw-bar head extends into an end recess in

the hook formed by spaced cheek-plates. The cheek-plates and the draw bar head are provided with registering apertures for receiving a coupling pin.

The coupling pin comprises upper and lower sections having mitered adjacent extremities and provided with a dovetail groove and fin respectively which are formed to retain the sides of the two sections substantially in alinement and to prevent separation of the sections when they are in extended position. A small pin in the lower portion extends into registering grooves in the lower cheek-plate and draw-bar head respectively and engages in a groove in the upper cheek-plate which has an inclined bottom side for preventing separation of the coupling pin from the rest of the device and wedgingly holding the lower section of the coupling pin temporarily in an inoperative position. When the upper part of the coupling pin is released, it falls downwardly relative to the lower section and the mitered extremities produce a lateral wedging action against the sides of the aperture in the upper cheek-plate which securely holds the coupling pin in inoperative position until parts thereof are jarred into alinement by the vibration caused when two cars are bumped together during coupling operations. When the parts of the coupling pin become in alinement, the coupling pin falls into operative position.

In the form shown, a coupling hook 1 comprising upper and lower cheek-plates 2 and 3 respectively, is pivotally mounted by a pin 4 on the head 5 of the draw-bar 6. The head of the draw-bar extends into an end recess in the hook member 1 between the upper and lower cheek-plates 2 and 3. As indicated in Fig. 1 the draw-bars of opposite ends of cars are provided with complementary coupling hooks, in which the hooked extremities extend from opposite sides of the hook members.

When cars are bumped together during coupling operation the coupling hooks are moved from the open position shown in Fig. 2 to the closed position shown in Fig. 1.

The upper and lower cheek plates 2 and 3 are provided with rectangular slots 7 and 8 respectively, which register with a corre-

sponding rectangular slot 9 in the head 5 of the draw-bar, when the coupling hook is in closed position. A coupling pin comprising upper and lower sections 10 and 11 respectively, is provided in the slots in the cheek-plates and head 5 for securing the hook member 1 in the closed position shown in Fig. 1.

The adjacent extremities of the sections 10 and 11 of the coupling pin are mitered, and 10 the upper section provided with a tapered dovetailed groove 12 for receiving a tapered dovetailed fin 13 on the lower section 11. The dovetailed joint formed by the slot 12 and fin 13 retains the surfaces of the upper 15 and lower sections 10 and 11 of the pin, substantially in alinement when the sections are in the extended position shown in Fig. 7. When the sections are in extended position the pin will fall freely through the slots in 20 the cheek-plates and head 5 when they are in registration.

A pin 14 projects from the right-hand side of the lower section 11 as viewed in Figs. 3 and 4. This pin extends into slots 15 and 16 25 in the draw-bar head 5 and the lower cheek-plate 3 respectively. A slot 17 in the upper cheek-plate 2 is provided for receiving the pin 14 when it is in its raised position. This slot has an inclined end wall 18 against which 30 the pin 14 abuts for preventing separation of the coupling pin from the coupling hook. The inclined end wall 18 also serves to urge the lower section 11 of the coupling pin into the position shown in Fig. 5, wherein it is 35 temporarily restrained from falling by the wedging action between the pin 14 and the inclined wall 18.

When the device is installed on a car the head 19 of the coupling pin is pivotally connected to a lever, not shown in the accompanying drawings, which extends outwardly to the side of the car, by means of which the pin may be raised to inoperative position. When the pin is raised by the levers, the lower 45 section becomes slightly wedged in the slot 7 of the upper cheek-plate 2 in the manner shown in Fig. 5. This wedging action temporarily holds the lower section in its uppermost position. When the upper section 10 is 50 released it falls downwardly relative to the lower section 11 and the mitered extremities of the two sections cause them to assume the offset position shown in Fig. 4. The movement of the upper section 10 relative to the 55 lower section 11 causes the pin 14 to be disengaged from the inclined wall 18 and the pin is retained in an inoperative position by the wedging action caused by the offset arrangement of its upper and lower sections.

In the above manner, the pin may be manually moved to an inoperative position and automatically retained in that inoperative position without manual assistance. When 60 the pin is in the position shown in Fig. 4 and

cars are bumped together during coupling operations, the vibration resulting jars the sections of the pin substantially into alinement with each other and permits the pin to fall through the slots 8 and 9 in the lower cheek-plate 3 and head 5 respectively into an operative position.

By means of the construction described, any number of coupling hooks may be set in open position with the pins thereof held in an 70 inoperative position. Then when the cars are bumped together the coupling hooks are secured in closed position by the falling of the coupling pin, which movement takes place without manual assistance and without requiring workmen to follow the dangerous practice of entering between the cars.

Although but one specific embodiment of my invention has been herein shown and described, it will be understood that details of the construction shown may be altered or omitted without departing from the spirit of this invention, as defined by the following claim.

I claim:

A car-coupling device comprising a draw-bar, a coupling member mounted on said draw-bar for connecting with the draw-bar of another car, a pin slidably mounted in apertures in said coupling member and draw-bar for retaining said coupling member in an operative position comprising relatively movable parts having mitered adjacent extremities for wedgingly securing said pin in an adjusted inoperative position when the 100 pin is lifted and then released, and a dovetailed joint between said parts for securing the same together, said joint being adapted to limit the relative extension of said bar for alining the sides thereof when the device is 105 subjected to jarring by coupling operations for automatically releasing said pin when said apertures are in alinement.

Signed at Chicago this 26th day of March, 1929.

VALENTY WROCLAWSKI.
